UNITED STATES PATENT OFFICE.

JAMES MONTGOMERY, OF MARSEILLES, ILLINOIS, ASSIGNOR TO SAMUEL H. MONTGOMERY, OF SAME PLACE.

FOLDING CRATE.

SPECIFICATION forming part of Letters Patent No. 532,684, dated January 15, 1895.

Application filed November 14, 1894. Serial No. 528,745. (No model.)

To all whom it may concern:

Be it known that I, JAMES MONTGOMERY, a citizen of the United States of America, residing at Marseilles, in the county of La Salle 5 and State of Illinois, have invented certain new and useful Improvements in Folding Crates, of which the following is a specification, reference being had therein to the accompanying drawings and the letters of reference thereon, forming a part of this specification, in which—

Figure 1 is a perspective view of the crate as it would appear ready for use. Fig. 2 is a perspective view of the crate as it would appear folded. Fig. 3 is a detail perspective view of one of the upper corners of the crate, showing a button for holding the cover in place when the crate is ready for use as shown in Fig. 1. Fig. 4 is a plan detail view 20 showing a portion of the cover and of the side and end of the crate, and a spring attached to the end for preventing the side from falling down. Fig. 5 is a cross sectional view of Fig. 2, and Fig. 6 is a detail perspective view 25 of one of the lower corners of the crate showing a corner block bolted to the bottom, and showing a slidable bolt on the upper end of said block for holding the cover in place when the crate is folded as shown in Fig. 2.

30 This invention relates to certain improvements in folding crates used for shipping purposes, which improvements are fully set forth and explained in the following specification and claim.

35 Referring to the drawings A represents the bottom of the crate made of boards resting on cross sills and nailed thereto. To each corner of said bottom is secured a short corner block B by means of a bolt O. The ends G and 40 sides H are pivotally connected to said corner blocks as shown in the broken lines in Fig. 6, in such manner that the ends and sides may fold down on the bottom A as shown in Fig. 5, the sides folding over the ends.

45 S is a flat spring attached to the inner upper sides of the ends as shown in Fig. 4, and in broken lines in Fig. 3, so arranged that their free ends will engage the inner upper

sides of the sides H to prevent the sides from falling down when the crate is in the position 50 shown in Fig. 1.

D is a cover made of slats and having its sides and ends flanged so as to set down over and inclose the sides H and ends G of the crate at their upper sides so they cannot spread 55 apart by reason of pressure of material within the crate. When said cover is in position as shown in Fig. 1, it is held down to its place by means of buttons F attached to the top corners of the ends G as shown particularly in 60 Fig. 3.

When the crate is folded by means of turning down the sides and ends as shown in Figs. 2 and 5, the cover D is placed so as to rest on the folded sides H, and so its flanged sides 65 and ends will inclose the folded crate, and is secured to its place by means of the 70 slidable bolts C on the upper ends of the corner blocks B as shown more particularly in Figs. 5 and 6.

F is a hinged slat which forms a door in the cover for access to the interior of the crate.

By means of such construction the crate is adapted to be folded and maintained in such folded position to enable it to be shipped back 75 to the point of its departure in a much smaller and more compact shape than if it could not be folded.

I am aware that crates made to fold have been heretofore used, but I am not aware of 80 such construction of crate, wherein the ends and sides are pivotally connected to corner blocks bolted to the floor, and wherein the cover is held in its place both while the crate is in use or folded by the means shown. This 85 construction dispenses with the use of metal hinges such as are generally in use for hinging the sides and ends to the floor, or bottom, and which are much more liable to become broken and unfit for use.

Having thus described my invention, what I claim as new, and desire to secure by Letters Patent, is as follows:

The combination of the bottom A having the corner blocks B bolted thereto, the corner blocks B having the slidable bolts C on

their upper ends, the sides H and ends G pivotally connected to said corner blocks in such manner that said ends and sides may fold down on said bottom, the buttons E on the 5 upper corners of said ends and the cover D having its sides and ends flanged for inclosing the sides and ends of the crate, all ar-

ranged to operate substantially as and for the purpose set forth.

JAMES MONTGOMERY.
